UNITED STATES PATENT OFFICE.

WILLIAM G. TAYLOR, OF PITTSBURG, PENNSYLVANIA, ASSIGNOR TO THE
TAYLOR BURNER & ELECTROPLATING CO., LIMITED, OF SAME PLACE.

DESIGN FOR A GAS-BURNER.

SPECIFICATION forming part of Design No. 26,149, dated October 6, 1896.

Application filed February 26, 1896. Serial No. 580,906. Term of patent 14 years.

To all whom it may concern:

Be it known that I, WILLIAM G. TAYLOR, of Pittsburg, in the county of Allegheny and State of Pennsylvania, have invented a new and original Design for Gas-Burners, of which the following is a full, clear, and exact description.

In the drawings, Figure 1 is a front elevation of a burner made in accordance with my design, and Fig. 2 is a cross-section on the line II II of Fig. 1.

2 represents the face of the burner, consisting of an upright plate with an outwardly-

convex curvature having parallel transverse grooves 3, separated by prominent ridges 4, 15 of woolly appearance, and 5 are perforations in the grooves.

I claim—

The design for gas-burners substantially as herein shown and described. 20

In testimony whereof I have hereunto set my hand.

WILLIAM G. TAYLOR.
